ROTARY INTERNAL COMBUSTION ENGINE

Ernest J. Serpas, New Orleans, La., assignor of
two-fifths to J. S. Waterman, New Orleans, La.Original application August 27, 1937, Serial No.
161,190. Divided and this application March
27, 1940, Serial No. 326,293

5 Claims. (Cl. 123—43)

This invention relates to rotary internal combustion engines, and is a division of my co-pending application Serial No. 161,190, filed August 27, 1937, for Rotary liquid fuel injecting internal combustion engine.

An object of this invention is to provide in a rotary internal combustion engine of the compression firing type, an improved means for injecting liquid fuel into the combustion chambers.

Another object of this invention is to provide in an internal combustion engine of the two-cycle type an adjustable fuel injecting means which is mechanically operable by rotation of the engine to inject the desired quantity of liquid fuel into the engine to thereby regulate the speed of the engine.

A further object of this invention is to provide an improved means for admitting air into the combustion chambers, the incoming air assisting in the scavenging of the exhaust gases.

A still further object of this invention is to provide an improved fuel injecting means for an engine of this type including pairs of injecting members and manually adjustable operating means therefor for regulating the quantity of fuel injected by said members.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a vertical sectional view taken longitudinally through a rotary internal combustion engine embodying my invention.

Figure 2 is a horizontal sectional view taken on the lines 2—2 of Fig. 1.

Figure 3 is an end elevation of the engine with the driving head removed.

Figure 4 is a sectional view taken on the line 4—4 of Fig. 1.

Figure 5 is a perspective view of the injector operator and regulator.

Figure 6 is a perspective view of one of the fuel injectors.

Figure 7 is a perspective view of the adjusting key for the injector operator and regulator.

Figure 8 is a perspective view of the key adjusting rod.

Referring to the drawings, the numeral 10 designates a base structure provided with a standard or supporting leg 11 rising therefrom. The standard or supporting leg 11 is provided at its upper end with a bearing or boss 13 in which

one end of a crankshaft 12 engages. The crankshaft 12 is provided with a longitudinal keyway 14, and the bearing or boss 13 is also provided with a complementary keyway 15 in which a key 16 engages so as to hold the crankshaft 12 against rotation relative to the boss or bearing 13.

The crankshaft 12 is provided with an offset or crank 17 and with a relatively short extension 18 which is coaxial with the shaft 12. A rotary driving casing generally designated as 19 engages about the shaft 12 and the extension 18, and encloses the offset crank 17, as shown in Figure 1. The driving casing 19 comprises an outer driving head 20 and an inner driving head 21 which are fixedly secured together by means of fastening devices 22. The fastening devices 22 engage through flanges 23 and 24 carried by the heads 20 and 21, respectively.

The driving head 20 is formed with a disc-shaped wall 25 having a hub or bearing 26 at the center thereof which is concentric to the stub shaft 18. An end wall 27 is formed integral with the hub 26, and this wall 27 is provided with a central opening 28, the purpose for which will be hereinafter described.

A lubricant reservoir, generally designated as 29 is carried by the end wall 25 of the head 20, and comprises a cylindrical wall 30 which is integral with the wall 25 and a disc-shaped end wall 31. A driving shaft 32 is carried by the end wall 31, the shaft 32 being provided with an annular flange 33 and an outwardly offset flange 34 which is detachably secured to the end wall 31 by fastening devices 35. Preferably the flange 33 engages in an opening 36 formed in the end wall 31 so that the driving shaft 32 will be held concentrically of the reservoir 29 and coaxial with the shafts 12 and 18.

The driving shaft 32 is provided with a pair of ports 37 which are formed in bosses 38 integral with the shaft 32, and the ports 37 may be closed by means of threaded plugs 39. The ports 37 communicate with an axial chamber 40 formed in the inner end of the shaft 32, and the chamber 40 communicates with the interior of the reservoir 29 so that this reservoir may be readily filled with a lubricant. The lubricant in the reservoir 29 is picked up by means of a tubular member 41 which is provided with a cut-out 42 at its outer or upper end, and the tubular member 41 is fixed to a hub 43 which is keyed or otherwise fixed to a reduced stub 44 carried by the shaft 18. The shaft 18 and the stub 44 are provided with an axial oil duct 45 which at one end communicates with a lateral passage 46. The passage 46 com-

municates with the inner end of the tubular member 41 so that the oil picked up by the tubular member 41 will gravitatingly flow downwardly therethrough, through the passage 46 and into the duct 45.

The periphery of the offset 17 is lubricated by means of a V-shaped duct 47 which has the apex thereof terminating at the periphery of the offset 17 and one divergent side thereof communicating with the inner end of the duct 45. The opposite divergent side of the duct 47 communicates with an axial duct 48 formed in the adjacent end of the shaft 12. A lateral passage 49 is formed in the shaft 12, one end of the passage 49 communicating with the duct 48, and the other end of the passage 49 communicating with the periphery of the shaft 12.

The casing 19 is provided with an annular piston cylinder 50 having one part 51 formed with the head 20, and a complementary part 52 formed with the head 21. Pairs of longitudinally arcuate pistons 53 and 54 are slidable in the cylinder 50, and these pistons are formed with recessed portions 55 and 56, respectively, in their confronting ends which form part of a combustion chamber when the pistons are moved toward each other.

A pair of piston carrying arms 57 and 58 extend diametrically of the casing 19, and these arms are provided at their centers with cylindrical hubs 59 and 60, respectively, which rotatably engage the shaft members 18 and 12, respectively. The arm 57 is provided at each end thereof with an L-shaped connecting rod 61 through which a wrist pin 62 engages, the pin 62 engaging through the piston 53. The arm or carrier 58 is also provided at the opposite ends thereof with an L-shaped connecting rod or member 63, and a wrist pin 64 engages through one leg of the connecting member 63 and also through the piston 54. The connecting rods or members 61 and 63 extend through elongated openings 65 and 66 formed in the casing 19 which communicate with the cylinder 50 and with the interior of the casing 19.

Rotary movement of the casing 19 is effected by means of a cross head 67 which is carried by one end of a connecting rod 68, the opposite end of the rod 68 being mounted on the offset crank 17. The heads 20 and 21 are provided with radial cross head guides 69 and 70, respectively, and the cross head 67 has rotatably mounted on the opposite ends thereof a pair of rollers 71 and 72 which engage in the guides 69 and 70, respectively. The rocking movement of the piston carriers 57 and 58 is communicated to the cross head 67 by means of a pair of links 73 and 74, each of which has one end thereof pivotally mounted on the cross head 67, and the link 73 is disposed on the side of the connecting rod 68 opposite from the link 74. The other end of link 73 is pivotally mounted on a pin 75 engaging the piston carrier 57, and the other end of link 74 is pivotally mounted on a pin 76 engaging the piston carrier 58.

The cylinder 50 is provided with a plurality of circumferentially spaced apart intake ports 77, and a valve structure generally designated as 78 engages within the intake port 77. The valve structure 78 comprises a tubular member 79 which is threaded through the wall 80 of the inner head 21, and is also disposed in the cylindrical wall 81 of the head 21. The tubular member 79 is provided with a constricted intermediate portion 82 which is preferably disposed within the cylinder 50, the inner side of the

constricted portion 82 forming a valve seat upon which a valve head 83 is adapted to engage. The valve head 83 is carried by a valve stem 84 slideable through the constricted portion 82, and a spring 85 engages about the stem 84 and constantly urges the valve head 83 against the seat. The inner end portion 86 of the tubular member 79 is provided with an axial plug 87, and also with a lateral discharge port 88 discharging into and at the innermost part of the firing chamber 50 and directed away from the axis of the engine in order that the centrifugal force acts to throw off the fuel oil from the mouth of the discharge port 88 and to sweep it through the compressed air in the firing chamber. The outer end of the tubular member is also closed by means of a threaded plug 89.

The end wall 80 is provided with a radial duct or passage 90 for each valve structure 78, the tubular member 79 being provided with a lateral passage 91 communicating with the outer end of the duct 90. The end wall 80 is provided with an annular flange 92, and a fuel injector cylinder 93 is threaded into this flange 92 and communicates at its inner end with the duct 90. The cylinder 93 is provided with a fuel intake port 94 inwardly of its outer end, and a fuel injecting piston 95 is slidable in the cylinder 93. The piston 95 is formed with a fuel receiving chamber or recess 96 which opens through the inner end of the piston 95 and through the periphery thereof. The recess 96 is adapted to partially register with the intake port 94 in one position of the piston 95 and to be subsequently moved inwardly and out of register with the intake port 94, as will be hereinafter described.

Each piston 95 has fixed to the outer end thereof a head or annular plate 97, and an expanding spring 98 engages about the exterior of the cylinder 93, one end of the spring 98 bearing against the flange 92 and the opposite end thereof bearing against the head or plate 97. The plate 97 is provided with a key 99 which is adapted to slidably engage in a keyway 100 formed on the inner surface of a cylindrical body 101 which is carried by the flange 92 and projects outwardly or rearwardly thereof. The key 99 holds the plate 97 against rotation and thus holds the piston 95 against rotation so that the recess 96 may register with the intake port 94 when the piston 95 is in a fuel receiving position.

The cylindrical body 101 forms a fuel chamber 102 in which liquid fuel is discharged under pressure, the fuel entering the chamber 102 through a discharge passage 103 formed in the shaft 12. The discharge passage 103 communicates with an axial passage or bore 104, and a fuel pipe 105 is connected with the outer end of the passage 104 by means of a connector 106. The opposite end of the fuel pipe 105 is connected to a pump housing 107 having an intake pipe 108. The pump structure disposed in the pump housing 107 is a conventional pump structure, the details of which are well known and therefore it is not deemed necessary to describe such structure.

The fuel chamber 101 is provided with a head 109 which is threaded onto the body 101, and the head 109 is provided with an annular groove 110 in which a sealing ring 111 engages. The ring 111 engages in the interior of a cylindrical flange 112 which is carried by the standard 11, and a second cylindrical flange 113 is carried by the flange 112, being connected thereto by means of an annular flange 114. A cylindrical member

115 is fixed to the end wall 80 and has a portion thereof engaging within the cylindrical member 113. The cylindrical member 115 is provided with an annular groove 116 in which a sealing ring 117 engages, the ring 117 engaging the interior of the cylindrical member 113. The cylindrical member 115 is rotatable with the head 80 and rotates within the cylindrical member 113, the latter member being stationary.

An injector operating member, generally designated as 118 is loosely mounted on the shaft 12 within the fuel chamber 102, and this operating member 118 comprises a plate 119 formed with a hub or bushing 120. The plate 119 is provided on its inner face with an outer series of cam lobes 121 and an inner series of cam lobes 121a. The cam lobes 121 confront cam engaging pins 122 which are carried by the plates 97, and the cam lobes 121a confront cam engaging pins 122a carried by plates 97a which are diametrically opposed to the plates 97. The plates 97a are carried by pistons 95a which are similar in every detail to the pistons 95.

The injector operating member 110 is adjusted lengthwise of the shaft 12 by means of a key 123 which is carried by a slide 124, slideable in a guide recess 125 formed in the shaft 12. A keeper 126 is fixed to the plate 119 and engages one end of the key 123 and holds the key 123 against movement relative to the plate 119. An operating or adjusting rod 127 is slideable in a longitudinal opening 128 formed in the shaft 12, one end of the rod 127 being threaded into the slide 124, and the other end of the rod being formed with an eye 129. An adjusting lever 130 is pivotally mounted on a pivot 131 carried by an ear 132 which is fixed to the bearing 13, and one end of the lever 130 is connected to the rod 127 by means of a pin or pivot 132 which engages through the eye 133.

A thrust bearing 134 is interposed between the head 109 and the adjacent end of the bearing 13, and the head 109 is provided with gear teeth 135 on the outer or rear face thereof with which a pinion or driven gear 136 is adapted to mesh. The gear 136 is fixed to a pump shaft 137 which extends upwardly through a bushing 138 carried by the pump structure 107.

The space between the cylindrical member 115 and the cylindrical member 101 constitutes an air intake chamber 139, and the cylindrical member 113 is provided with an air intake duct 140 opening in the direction of the base 10. The wall 80 of the head 21 is provided with a plurality of air intake ports 141 so that air from the chamber 139 may enter the interior of the casing 19 and pass through the openings 65 into the cylinder 50.

The operation of the rotary internal combustion engine hereinbefore described is set forth in detail in my copending application Serial No. 161,190, but will be briefly set forth herein. The rotary casing 19 comprises a combined flywheel and cylinder, and this casing 19 is initially given rotary movement to start its operation. As the casing 19 rotates about the shafts 12 and 18, the pairs of pistons 53 and 54 are reciprocated back and forth in the annular cylinder 50. This reciprocation of the pistons 53 and 54 is obtained by swinging of the eccentrically mounted connecting rod 68 under the action of the toggle link members 73 and 74. As the connecting rod 68 is swung about the offset crank part 17, the crosshead 67 which not only forms a pivotal connection between the toggle links 73 and 74 with the connecting rod 68, but also forms a connection between the swinging connecting rod 68 and the casing 19

through engagement of the opposite ends of the crosshead member 67 in the radial guides 69 and 70 formed in the casing heads 20 and 21, respectively.

With the rotation of the casing 19 the gear teeth 135 will rotate the pump operating pinion or gear 136 so as to build up a pressure of fuel in the fuel chamber 102. During the greater portion of each complete revolution of the casing 19, the injector operating pins 122 carried by each injector will slidably contact with the flat face of the adjusting cam plate 118. There is one cam lobe 121 or 121a for each pin 122 or 122a, and each cam lobe is provided with a circular portion of the plate 119. There is a separate lobe for each injector 95 so that a charge of fuel will be injected into the compressed air between each pair of pistons 53 and 54. In the present instance the pistons 53 and 54 are double ended pistons, and when a pair of these pistons are in compressing position, one end of one piston is closely adjacent the confronting end of its associated piston, whereas the opposite ends of the pistons are on the exhaust stroke. As the positions of the carriers 57 and 58 change under the expansion of the gases, the opposite ends of the pistons 53 and 54 move to a compression stroke.

Assuming that the pistons 53 and 54 are in the position shown in Fig. 3, a diametrically opposed pair of injector pistons 95 will be forced inwardly by engagement of the cam lobes 121 and 121a with the pins 122 and 122a, respectively, so as to unseat the associated valve members 83 and permit the fuel to be discharged through the ports 88 into the compressed air which will immediately ignite the fuel and cause the pistons 53 and 54 at their ends 53a and 54a, respectively, to move apart on their power stroke, while at the same time the opposite ends 53b and 54b will move toward each other on their compression stroke. Due to the simultaneous reciprocation of the pistons 53 and 54 and the rotation thereof with the casing 19, the ends 53a and 54a will have only one compression and one exhaust stroke for each revolution, and the same is true for the opposite ends 53b and 54b.

At low speed the cam plate 119 is shifted to the left as viewed in Fig. 1 so that the outer ends of the fuel channels 96 of the plungers 95 will be disposed outwardly of the intake ports 94, thus providing movement of the plungers 95 without causing an injection of fuel sufficient to unseat the valve 83. As a consequence part of the charge of fuel oil ahead of the plunger 95 is forced to back up or return to chamber 102 through port 94. This has the effect of not only delaying the fuel injection, but also of restricting the amount of fuel injected as a portion of the stroke of a plunger 95 is had without injection of fuel, although the endwise movement of a plunger 95 is the same for both low and high speeds.

At high speed the cam plate 119 is moved forwardly, or to the right as viewed in Fig. 1, so that the plungers 95 act to close the inlet ports 94 at an earlier period and permitting less of the charge of fuel oil ahead of the plunger to back up or return through the channels 96 and the intake ports 94, thus causing a greater or full charge of fuel to be injected in the firing chambers of the engine.

The fuel injecting means hereinbefore described will positively inject measured quantities of fuel between the ends of the pairs of pistons which are on their compression stroke, and the quantity of fuel injected by the pistons

or plungers 96 will provide a regulating means for regulating the speed of the engine.

The exhausted gases will discharge from the cylinder 50 through exhaust ports 142 which are formed in the cylinder 50, and the exhaust gases will then enter a muffler 143 carried by the casing 19 which is annular in side elevation and U-shaped in transverse section.

It is, of course, understood that various changes and modifications may be made in the details of construction of the hereinbefore described embodiment of this invention, such changes and modifications being limited only by the scope of the appended claims.

What is claimed is:

1. In a rotary internal combustion engine including a stationary crank shaft, a rotatable cylinder housing, pistons slideable in said housing, and means connecting said pistons with said crank shaft and said housing; fuel injection means for said housing comprising a plurality of circumferentially spaced apart spring-pressed plungers carried by said housing, a plate slideable on said crank shaft, said plate having a recess communicating with the bore thereof, cam lobes carried by the side of said plate confronting said plungers, said crank shaft having a recess communicating with the recess of said plate, a plate operating rod slideable interiorly of said crank shaft, a key member carried by said rod engageable in the recess of said plate whereby to adjust said plate longitudinally of said crank shaft upon longitudinal adjustment of said key member, and an operating member for said rod.

2. In a fuel injector for rotary internal combustion engines, a stationary shaft, an annular rotatable cylinder carrier, a fuel injecting cylinder mounted on said cylinder carrier, a source of fuel supply in communication with said cylinder, a fuel injecting plunger disposed in said cylinder, a cam mechanism carried by said stationary shaft adapted to engage said plunger and move it longitudinally of said cylinder, resilient means urging the plunger towards the cam mechanism, and means to adjust the cam mechanism axially of said plunger to control the movement of the plunger in the cylinder.

3. In a fuel injector for rotary internal combustion engines, a stationary shaft, an annular rotatable cylinder carrier, a fuel injecting casing mounted on said cylinder carrier, a source of fuel supply in communication with said cylinder, a fuel injecting plunger disposed in said casing for reciprocating motion, a cam plate

having a cam element carried by said stationary shaft adapted to engage the plunger and move it in one direction in its casing, resilient means urging the plunger in the opposite direction towards said cam plate, means to cause relative rotative movement between the cam plate and the plunger and casing assembly to bring the cam element into operative contact with the plunger at spaced intervals, and means to adjust the cam plate axially of said plunger and casing to regulate the movement of the plunger in the casing.

4. In a fuel injector for rotary internal combustion engines, a shaft, a housing operatively associated therewith in concentric relation thereto, a fuel injecting cylinder carried by the housing, a source of fuel supply communicating with said cylinder, a fuel injecting plunger carried by the housing, a source of fuel supply communicating with said cylinder for reciprocating movement, a cam plate carried by the shaft and keyed thereto, said cam plate having a lobe adapted to engage the plunger and move it in one direction in the cylinder, resilient means urging the plunger in the opposite direction towards said cam plate, means to cause relative rotative movement between the housing and shaft to bring the cam lobe into operative engagement with the plunger at spaced intervals, and means to adjust the cam plate axially of the shaft to regulate the movement of the plunger in the cylinder.

5. In a fuel injector for rotary internal combustion engines, a shaft, a housing operatively associated therewith in concentric relation thereto, a plurality of fuel injecting cylinders carried by said housing at points spaced radially from said shaft, a source of fuel supply communicating with the cylinders, a fuel injecting plunger disposed in each cylinder for reciprocating movement, a cam plate carried by the shaft and keyed thereto, said cam plate having a plurality of lobes spaced radially apart, each lobe adapted to engage one of the fuel injecting plungers to move it in one direction in its cylinder, resilient means urging each plunger in the opposite direction towards said cam plate, means to cause relative rotative movement between the shaft and housing to bring the cam lobes into operative engagement with the fuel injecting plungers, and means to adjust the cam plate axially of the shaft to regulate the movement of the plungers in their cylinders.

ERNEST J. SERPAS.
